IMPACT FORGING

Alfred H. Oelkers, Chicago, Ill.

Application June 5, 1931, Serial No. 542,222

20 Claims. (Cl. 78—20)

This invention pertains to impact forging, and more particularly to a process and means for performing heavy duty impact forging.

An object of this invention is to provide a process for impact forging.

Another object of the invention is to provide a device for impact forging.

Yet another object of the invention is to provide a machine in which the impact is the collision of two oppositely moving masses of substantially the same weight collided when moving at substantially the same speed.

A further object of the invention is to provide a device wherein the blank is in contact with the forming dies for only a very short time.

Still another object of the invention is to provide a device wherein, after the forming has occurred, the dies will be quickly separated to permit the discharge of the formed blank.

A yet further object of the invention is to provide a device for forming heavy or other articles quickly and adequately.

With these and various other objects in view, the invention may consist of certain novel features of construction and operation as will be more fully described and particularly pointed out in the specification, drawings and claims appended hereto.

In the drawings, which illustrate embodiments of the device and wherein like reference characters are used to designate like parts—

Figure 1 is a side elevation of a device for impact forging, the dotted lines showing the position of parts of the device at the moment of forging;

Figure 2 is a modified form of a device embodying the invention, the dotted lines showing the position of parts of the device at the moment of forging;

Figure 3 is a fragmentary elevation of the forging vehicles showing the position thereof before the forging operation;

Figure 4 is a fragmentary elevation of the vehicle shown in Figure 3, just prior to the forging operation;

Figure 5 is a fragmentary sectional elevation through the vehicles showing the position of the dies at the moment that the forging operation occurs;

Figure 6 is a view corresponding to Figure 1 showing another modified form of the device;

Figure 7 is a transverse sectional elevation through the tracks in the device shown in Figure 6, showing an end elevation of the hammer car;

Figure 8 is a side elevation of the blank holding

device or forming press for the modification shown in Figure 6;

Figure 9 is an end elevation partly in section of the forming press shown in Figure 8;

Figure 10 is a top plan of the forming press shown in Figure 8;

Figure 11 is a longitudinal sectional elevation of the forming press taken substantially in the plane indicated by the line 11—11 of Figure 10;

Figure 12 is a side elevation of another form of the device;

Figure 13 is a transverse sectional elevation taken substantially in the plane indicated by the line 13—13 of Figure 12;

Figure 14 is a transverse elevation of the anvil shown in Figure 12, the same showing a front view of the die on the anvil and showing the tongs holding the blank ready for the forging process; and

Figure 15 is a side elevation of still another form of the device.

Referring first of all more particularly to the forms of the device illustrated in Figures 1 to 5 inclusive, as shown, substantially the same form of hammer car is used with each modification.

In Figure 1, hammer cars 10 and 12 are provided with flanged wheels 14 mounted on a substantially arcuate track 16 which may be an element of a circle. At each end of the track a platform 18 is provided on which a hoisting engine 20 is mounted connected through the cables 22 to the respective hammer cars 10 and 12. In the modification shown in Figure 2, hammer cars 10 and 12 provided with the flanged wheels 14 are mounted on a level or straight track 24. Power is transmitted from the prime mover, power plant, or engine 25 through suitable gearing 26—28 to the endless cables 30 and 32, and each car 10 and 12 is provided with a releasing device indicated at 34 adapted to connect the car to the respective cable, after which the cars may be accelerated toward each other by the power plant 25 until impact occurs, when the device 34 may release the cars from the cable, or may operate means not shown to shut off the prime mover or power plant 25. After impact the power plant may be reversed, or the lower portion of the cable engaged, to return the cars to their initial starting position.

The hammer car 10 is provided with a body portion 36 of great weight, the body portion being provided with pedestals 38 for receiving the axles 40 of the wheels 14. The die 42 is mounted on the end of the body 36 facing the die 44 mounted on the body 46 of the hammer car 12. The

body 46 is also provided with pedestals 48 for receiving axles 50 of the respective wheels 14 thereof. The body 36 adjacent the die 44 is provided with outwardly extending lugs or trunnions 52 disposed at the top and bottom and on each side of the die. The body 46 is provided with tongs pivotally mounted at 54 thereof, the tongs including an upper member 56 extending toward the car 10 and provided with an upwardly flaring portion 58. The member 56 is also provided with an extension 60 adapted to be adjusted by means of the set screw 62 mounted in the lug 64 on the body 46. The lower member 66 making up the tongs is pivoted at 54 and extends toward the car 10 and is provided with a downwardly deflected portion 68. The members 56 and 66 on each side of the car are respectively connected by straps 70 and 72 respectively adapted to hold the blank 74. The tong members 56 and 66 are urged toward each other, that is, in blank holding position, by means of the plungers 76 and 78 mounted on the body 46 and urged toward the tongs by means of the expansion springs 80 and 82. Thus it will be seen that when the blank 74 is mounted between the members 70 and 72 and the cars accelerated toward each other, the blank is spaced from the die 44. The object of holding the blank in the path of the dies and not in contact therewith is to protect the dies from the damaging effect of the heat which they would absorb from the hot metal were it in contact with them.

Prior to contact between the dies the lugs 52 engage the deflected portions 58 and 68 of the members 56 and 66 to cause spreading of the tongs against the plungers 76 and 78. Spreading of the tongs permits the dies 42 and 44 to be brought together to confine the blank 74 therebetween, the members of the blanks being preferably provided with risers 84 for accommodating the excess metal. As the impact between the cars is terrific, the cars will rebound to open the dies, whereupon the formed blank will immediately fall out, or can be forced out so that the hot metal will not be in contact with the dies for any longer period than is necessary. After rebound, brake mechanism (not shown) may be applied mechanically at the side of the track magnetically, etc., to maintain the cars separated.

In the modifications shown in Figures 6 to 11 inclusive an arcuate track 100 is provided, the track terminating at each end adjacent a platform 102 on which a hoisting engine 104 is mounted. In this case a plurality of hammer cars 106 are disposed on each side of the center of the track 100, and are connected to the respective hoisting engines 104 through the cables 108. The cars are provided with the body portion 110 of great weight, each body being provided with the pedestal portions 112 to which the axles 114 are journaled. Flanged wheels 116 are mounted on the axles and cooperate with the track 100. The cars are provided adjacent the pedestals with the openings 118 through which the flexible connection 120 passes and serves to connect the cars together.

The track 100 is preferably of constant curvature, as a portion of a circle. The faces of adjacent cars may be kept constantly in engagement with each other so that there is no slack, this adjustment being made possible by means of a flexible connection 120. In this case the cars preferably do not carry the blank. Instead, a forming press 122 is mounted on the track ad-

5 jacent the center thereof in a position where it may be contacted at or near the same time by each set of cars. The forming press is provided with a base 124 slidably mounted on the tracks 100. Spaced die holders 126 and 128 are mounted on the base, said die holders being movable toward each other. In the embodiment shown, double acting pneumatic cylinders 130 are provided for moving the die 128 toward the die 126. In this case the piston rod 132 of the pneumatic cylinder 130 is connected to the die holder 128 through the bracket 134 and the pin 136, so that operation of the cylinders 130 causes the piston rod 132 to move the die 128 with respect to the die 126. Suitable guide means 142 are provided for the die holders so that they will not become misaligned. In this case the cylindrical guide members 142 are mounted in the sockets 144 provided on the member 126 and are adapted to extend through embracing members 146 provided 20 on the die-holding member 126. Each die-holding member 126 and 128 is provided with a striking or impact plate 148, and the dies 138 and 140 are releasably connected to the members 126 and 128 by means of the retainer 150, the dies prefer- 25 ably being mounted in sockets 152 in the members 126 and 128.

The blank is mounted in the cradle 154, said cradle being vertically adjustable, the ends of the cradle being mounted on the vertically slid able 30 members 156 pivotally connected as at 158 to the link 160, said link being pivotally connected as at 162 to the lever 164, said lever being pivotally mounted on the shaft 166, the shaft being oscillated by means of the lever 168 pivotally connected to the piston rod of the operating cylinder 170. Movement of the lever 160 is limited by the adjustment 172 which consists essentially of a locking wheel 174 mounted on the threaded shaft 176, the shaft being adjustable in the nut 178 40 toward and away from the cylinder 170, the adjustment being effected by means of the hand wheel 180. After the required movement by the hand wheel 180 the hand wheel 174 can be tightened against the nut to prevent further movement 45 of the threaded shaft 176.

In operation, the blank is held in place by the cradle 154. The blank is then caught between the dies by operation of the cylinder 130, and the cylinder 170 is then operated to drop the cradle 50 from between the dies. The power plants 104 are released as in the case of the modification shown in Figure 1, whereupon the weight of the hammer cars causes them to approach and contact the impact plates 148 of the forming press, causing 55 a blank to be formed between the dies 138 and 140. After the blank has been formed the cars can be returned by their respective power plants 104 and the dies are separated by operation of the cylinder 130 as desired, and the cradle can be ele- 60 vated as the cylinder 130 is separating the dies to receive the formed blank, or separate means may be used.

In the device shown in Figures 12 to 14 inclusive, a horizontally movable ram 200 is mounted 65 on an underframe 201, said underframe being provided with oppositely extending shoulders 203 adapted to have guiding cooperation with track portions 205 braced to the foundation 207 by means of the brackets 209. The underframe is 70 provided with pedestals 202, the ram being mounted on the underframe by means of the straps 204, the pedestals being provided with wheel and axle assemblies 206, the wheels being in engagement with the track 208 mounted be- 75

tween the front and back stops 210 and 212 and on the foundation 207. The ram is provided with an explosion chamber 214 and a muffler 216, the ram being provided with a die 218 and spaced 5 upper and lower trunnions or lugs 220. The ram in initial position is disposed adjacent the back stop 212 having a plunger 222 mounted between the ram and back stop, the plunger extending through a bore in the ram to the explosion chamber. A normally stationary extremely heavy 10 anvil 224 is mounted adjacent the front stop 210 slidably mounted on the track 208, being limited in its movement toward the back stop by the brackets 226 and being provided with a plurality 15 of nests of springs 228 separating the anvil from the front stop. The anvil 224 is provided with the tongs 230 provided with the upper member 232 pivoted at 234, said member being provided with the adjusting extension 236 adapted to be 20 contacted by the adjusting screw 238 mounted in the bracket 240. The member 232 is provided with the upwardly flaring or deflected portion 242 and a lower member 244 is also pivoted at 234 and is provided with a downwardly deflected portion 246. Members 232 and 244 on opposite sides of the anvil are connected with upper and lower members 248 and 250 adapted to hold the blank 252 in spaced relation to the die 254 provided on the anvil and facing the die 218. 30 The tongs are urged to blank holding position by means of the plunger and spring members 254 and 256.

In operation, when the explosive is ignited, or a gas burned in the explosion chamber, the pressure forces the ram to move toward the anvil. 35 Movement of the die 218 toward the die 254 causes the plugs 220 to contact the members 242 and 246, separating the tongs and permitting the dies 218 and 254 to form the blank 252. The shock or impact which is not absorbed by the forming of the material between the dies sets 40 the anvil in motion toward the front stop 210 against the springs 228, the springs finally returning the anvil to the proper position for the 45 next operation.

In the form of device illustrated in Figure 15, a pendulum movement is contemplated. In this case hammers 300 are pivoted through the cables 302 as at 304 to the support 306, and the hammers 300 may either be provided with a die holding device such as the tongs illustrated and described with respect to figures 1 to 5 inclusive, and Figures 12 to 14 inclusive, or a device similar to the forming press described in Figures 8 to 11 55 inclusive, may be used, or any other convenient die-holding means. In this case the hammers 300 are retracted by the power plants 308 connected to the hammers by the cables 310, and at the proper time the power plants may permit the 60 hammers 300 to swing toward each other, effecting the forging operation. The hammers are preferably guided by the track 312 slidably and freely engaging the guide members 314 provided on the hammers.

65 With the devices shown it will of course be understood that very effective forging devices are provided, it being also understood that brakes of the magnetic, track, or other type, may be used to stop the hammers after rebound on any 70 of the modifications, if desired; and it is to be understood that I may make changes in the construction and in the combination and arrangement of the several parts, provided that such changes fall within the scope of the appended 75 claims.

I claim:

1. In a forging device, the combination of dies, an arcuate track, weighted means carrying said dies mounted on said track, means for moving said first named means to different parts of said track and releasing the same, whereby said weighted means bring said dies together by inertia. 5

2. In a forging device, the combination of an arcuate track, a blank holding device mounted on 10 said track, and hammers mounted on said track and movable toward said blank holding device by the inertia of said hammers.

3. A blank holding device including a body member, a die mounted thereon, spaced members 15 pivotally secured to said body and forming tongs, said members having deflected portions for separating said members, each of said members having members for holding a blank spaced from said die. 20

4. A blank holding device including a body member, a die mounted thereon, spaced members pivotally secured to said body and forming tongs, said members having deflected portions for separating said members, each of said members having 25 members for holding a blank spaced from said die, and means for urging said members toward each other.

5. In an apparatus for producing heavy forgings by single impact, oppositely disposed impact 30 transmitting members supported for normal gravitational movement towards each other, means for moving said members in opposite directions whereby, upon release of said means, said members develop considerable kinetic energy as they 35 approach each other, cooperating dies movably supported between and in the path of movement of said impact members and adapted to receive a hot metal blank therebetween, said blank being formed to shape by the impingement of said dies 40 produced by the substantially simultaneous impact in opposite directions received from said impact members.

6. In an apparatus for producing heavy forgings by single impact, a continuous track having 45 lateral portions at higher levels than the central portion, a pair of oppositely disposed impact transmitting members mounted on said track for normal gravitational movement towards each other, means for moving said members in opposite directions towards the ends of said track whereby, upon release of said means, said members develop considerable kinetic energy as they approach each other, a forming blank slidably mounted on the central portion of said track between 50 said members including a pair of relatively movable dies positioned for movement towards each other produced by the impact received from said impact members, said dies being adapted to receive and retain a hot metal blank therebetween 55 60 which is formed to shape by the impingement of said dies.

7. In a forging apparatus, a continuous track having lateral portions at a higher level than the median portion, a pair of hammers mounted for 65 movement on said tracks, means for moving said hammers to the opposite ends of said track so that said hammers upon release will move by gravity towards each other, dies carried by said hammers, means on one of said hammers for initially supporting a heated blank in spaced relation to the die on said hammer, and means on the other of said hammers for releasing said blank holding means as the hammers move to- 70 75

wards each other to permit forging of the blank by said dies.

8. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of dies operable under the impact received from said impact members to form to shape a metal blank disposed therebetween.
9. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said impact members, means on one of said members for initially supporting a blank, and means on the other of said members for releasing said blank holding means as the hammers move toward each other to permit forging of the blank by said dies.
10. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said impact members and operable under the impact received therefrom to form to shape a metal blank disposed therebetween.
11. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said track between said lateral portions, said dies being operable under the impact received from said impact members to form to shape a metal blank disposed therebetween.
12. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said impact members, means on one of said members for initially supporting a blank, and means on the other of said members for releasing said blank holding means as the hammers move toward each other to permit forging of the blank by said dies.
13. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said impact members, pivotally mounted arms disposed on each side of one of said members, straps connected to said arms for embracing a metal blank, and means for engaging said arms to release said blank as the hammers move toward each other to permit forging of the blank by said dies.
14. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said impact members, pivotally mounted arms disposed on each side of one of said members, straps connected to said arms for embracing a metal blank, means for urging said arms into blank engaging position, and means for engaging said arms to release said blank as the hammers move toward each other to permit forging of the blank by said dies.
15. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, and a pair of oppositely disposed dies mounted on said impact members, pivotally mounted arms disposed on each side of one of said members, straps connected to said arms for embracing a metal blank, means for urging said arms into blank engaging position, and means for engaging said arms to release said blank as the hammers move toward each other to permit forging of the blank by said dies.

ment toward each other down said inclinations, means for moving said members in opposite directions towards the ends of said track whereby, upon release of said means, said members accelerate through the force of gravity alone to develop kinetic energy as they approach each other, said inclination being of sufficient length to produce sufficient kinetic energy to develop a forging blow, a pair of oppositely disposed dies mounted on said impact members, pivotally mounted arms disposed on each side of one of said members, straps connected to said arms for embracing a metal blank, and means on the other of said members for engaging said arms to release said blank as the hammers move toward each other to permit forging of the blank by said dies.

16. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, a pair of oppositely disposed dies mounted on said impact members, pivotally mounted arms disposed on each side of one of said members, straps connected to said arms for embracing a metal blank, means for urging said arms into blank engaging position, and means on the other of said members for engaging said arms to release said blank as the hammers move toward each other to permit forging of the blank by said dies.

17. In a forging apparatus, the combination of a continuous track having lateral portions at higher levels than a portion therebetween presenting opposite inclinations, a pair of oppositely disposed impact transmitting devices mounted on said track for normal gravitational movement toward each other down said inclinations, each of said devices comprising a plurality of impact members connected together, and means for moving said devices in opposite directions toward the ends of said track whereby, upon release of said means, said devices accelerate through the force of gravity alone to develop kinetic energy as they approach each other, said

inclination being of sufficient length to produce sufficient kinetic energy to develop a forging blow.

18. In a forging apparatus, the combination of a continuous track having lateral portions at higher levels than a portion therebetween presenting opposite inclinations, a pair of oppositely disposed impact transmitting devices mounted on said track for normal gravitational movement toward each other down said inclinations, each of said devices comprising a plurality of impact members, means whereby said members are flexibly held in association with one another, and means for moving said devices in opposite directions toward the ends of said track whereby, upon release of said means, said devices accelerate through the force of gravity alone to develop kinetic energy as they approach each other, said inclination being of sufficient length to produce sufficient kinetic energy to develop a forging blow.

19. In an apparatus for producing forgings, the combination of a continuous track having lateral portions at higher levels than a portion therebetween presenting opposite inclinations, oppositely disposed impact transmitting members mounted on said track for gravitational movement toward each other down said inclinations, means for moving said members in opposite directions toward the ends of said track whereby, upon release of said means, said members accelerate through the force of gravity alone to develop kinetic energy as they approach each other, said inclination being of sufficient length to produce sufficient kinetic energy to develop a forging blow, die holding members mounted on said track between said lateral portions, dies mounted on each of said holding members, means for holding a metal blank between said dies when said die holding members are in spaced relation, and means for moving said members toward one another whereby said dies engage and hold said blank, said blank being formed to shape by said dies upon impact of said impact members with said die holding members.

20. In a forging apparatus, the combination of spaced rails and die holding means mounted on said rails, said means comprising a die holding member fixed to a base slidably mounted on said rails, a die holding member slidably mounted on said base, dies mounted on said members, and means for moving said second-named die holding member toward and away from said first-named die holding member.

ALFRED H. OELKERS. 55
